UNITED STATES PATENT OFFICE

124,220

DESIGN FOR A TEXTILE FABRIC

Sam B. Hyman, Los Angeles, Calif.

Application October 12, 1940, Serial No. 95,789

Term of patent 7 years

To all whom it may concern:

Be it known that I, Sam B. Hyman, a citizen of the United States and residing at Los Angeles, in the county of Los Angeles and State of California, have invented a new, original, and ornamental Design for a Textile Fabric, of which the following is a specification, reference being had to the accompanying drawing forming part thereof.

The figure of the drawing is a plan view of the textile fabric showing my new design.

I claim:

The ornamental design for a textile fabric, as shown.

SAM B. HYMAN.
